(57) **CLAIM**

The ornamental design for a pen, as shown and described.

DESCRIPTION

FIG. 1 is a front left perspective view of a pen showing our new design;

FIG. 2 is left side elevation view thereof;

FIG. 3 is a top plan view thereof;

FIG. 4 is a front elevation view thereof;

FIG. 5 is a right side elevation view thereof;

FIG. 6 is a bottom plan view thereof; and,

FIG. 7 is a rear elevation view thereof.

The stippled shading shown on a portion of the pen represents a surface texture.
